PROCESS FOR CATALYTIC CONVERSION OF
HYDROCARBONS

Louis S. Kassel, Chicago, Ill., assignor to Universal Oil Products Company, Chicago, Ill., a corporation of Delaware

Application November 30, 1939, Serial No. 306,934

11 Claims. (Cl. 196—52)

This invention relates to a process for the catalytic conversion of hydrocarbon oils into motor fuels of high antiknock value. More particularly, it concerns the conversion of hydrocarbon oils of petroleum origin into substantially olefin-free gasoline suitable for use as an aviation base fuel.

The use of various catalytic materials for the production of increased yields of high antiknock motor fuel has been practiced. Under certain conditions of operation involving temperatures in excess of approximately 850—900° F. and relatively low pressures, gasoline and gases containing large percentages of olefin hydrocarbons are produced by the catalytic cracking of hydrocarbon oils of higher than gasoline boiling range. The gasolines produced are of good antiknock value, which makes them particularly desirable for use as motor fuel.

When such gasolines are subjected to the action of certain catalytic materials at relatively low temperatures, e. g., of the order of 500—900° F., substantially olefin-free gasolines are obtained accompanied by little or no change in the antiknock value. As a consequence the combination of these two processes offers a good method of producing substantially saturated gasoline suitable for use in aviation fuels.

The catalytic materials employed in these reactions comprise particularly the so-called silica-alumina, silica-zirconia, or silica-alumina-zirconia composites made by the separate or simultaneous precipitation of silica and an oxide of alumina and/or zirconia under conditions such that alkali metal ions are eliminated. Other cracking catalysts such as acid-treated clays may also be used, although they are not necessarily exactly equivalent in their action.

The catalysts may be used for producing olefin-free gasoline, and after being substantially spent for this purpose, can be used at higher temperatures for producing additional yields of an olefin-containing gasoline.

Eventually the catalysts require regeneration in order to restore activity which has been decreased largely due to an accumulation of carbonaceous or hydrocarbonaceous deposits on their surfaces. In reactivating the catalytic materials, temperatures of the order of those employed in the high temperature cracking step or even higher are necessary, namely, approximately 900—1500° F. A combination process using a low temperature processing step followed by a high temperature processing step and finally by reactivation, offers advantages. The present invention

comprises a process utilizing these steps to produce substantially saturated gasoline of desirable properties from hydrocarbon oils.

In one specific embodiment the present invention comprises a continuous process for converting hydrocarbon oil into high yields of substantially olefin-free gasoline which consists in converting said hydrocarbon oil in a plurality of catalytic reactors serially arranged, wherein the repeated sequence of steps is carried out at each of said catalytic reactors, said sequence of steps comprising a primary step of contacting olefin-containing distillate from a secondary step about to be described with a cracking catalyst under conditions adequate to produce a substantially olefin-free gasoline, a secondary step of contacting said hydrocarbon oil with a cracking catalyst under conditions adequate to produce an olefin-containing distillate for conversion in said primary step, a tertiary step of reactivating spent catalyst at a temperature level beginning at that of the secondary step, and a quaternary step of completing reactivation while returning the temperature to the level of the primary step, the reactors operating in said primary and quaternary steps being maintained in heat exchange relationship with a circulating fluid heat exchange medium kept at a suitable relatively low temperature, and the reactors operating in said secondary and tertiary steps being maintained in heat exchange relationship with a separate circulating fluid heat exchange medium kept at a suitable relatively higher temperature, recovering the gasoline from said primary step and returning a portion of insufficiently converted oil to said primary and/or secondary steps for further conversion.

The two temperature levels are achieved and controlled by the use of two separate circuits of heat exchange fluids so arranged that each catalyst region may be brought into heat exchange relationship with the fluid in either circuit. One method of accomplishing this is illustrated in Fig. 2, which will be explained in detail later in the specifications. The materials which may be used as heat exchange media include low melting metals or alloys, alkali metal hydroxides, mixtures of salts melting below 450—500° F., etc.

Fig. 1 is an illustration of a process hook-up involving the use of the various temperature levels contemplated for processing and reactivation. The illustrations are diagrammatic and represent one embodiment of the principle involved, and should not be interpreted as limiting the invention to the exact apparatus or equip-

ment shown. Numerous types of reactors or variations of the type shown may be employed, and these are understood to be included within the scope of the present invention.

Fig. 2 illustrates diagrammatically a heat exchange system whereby the operation illustrated in Fig. 1 may be accomplished, reactors 1, 2, 3 and 4 in both Fig. 1 and Fig. 2 being identical.

Figs. 3, 4, 5, 6 and 7 illustrate diagrammatically variations in the setting of the respective switching valves illustrated in Fig. 2.

The apparatus consists essentially of four manifolded reactors. The reactors may comprise any suitable type, of which that illustrated is a simple diagrammatic representation consisting of one or more catalyst tubes or chambers disposed in a jacket or shell through which a heat exchange medium can be circulated. The entire operation involves a repeated cycle of four phases. During all these phases the flows to and from the entire group of reactors remain the same, but the flows to and from each separate reactor change with each change of phase. It will be sufficient therefore to describe the flow completely for a single phase, and more briefly for the other three. It is obvious that the choice of phase to be described first and completely is entirely arbitrary.

Referring to Fig. 1, the raw oil is introduced through line 5, valve 6, pump 7, line 8, valve 9 and line 10 to coil 11, which is disposed in heater 12, and wherein it is heated to a temperature within the range of approximately 850-1200° F. The oil then passes through line 13 and valve 14 to line 15 and valve 16, entering the catalyst tube 17 which is a part of reactor 2. The catalyst tube contains a suitable cracking catalyst and is disposed in shell 18 equipped with inlet and outlet lines 19 and 20 which provide a means for circulating a heat exchange medium around the reactor tube. It is understood that tube 17 may consist of a reaction chamber or a multiplicity of manifolded tubes containing catalyst. As previously mentioned, the hook-up for circulating the heat exchange medium is illustrated in Fig. 2. The reaction products leave reactor 2 through line 21 and valve 22, passing by way of line 23 to fractionator 24. Gaseous products are removed through line 25 and valve 26. These gases contain polymerizable olefin hydrocarbons which may be separately processed by known methods to produce high antiknock motor fuel. A residual oil may be withdrawn and removed from the system through line 27 and valve 28.

The insufficiently converted oil is passed through line 29, valve 30, line 31 and valve 31', which joins with line 10, and is thus recirculated to the cracking step. The gasoline from fractionator 24 is passed through line 33 and valve 34, pump 37 and valve 38 to coil 35, which is disposed in heater 36. The heated oil passes through line 39 and valve 40 to line 41 and valve 42 and thence into reaction tube 43, which is disposed in reactor 1, which is similar to reactor 2 and is equipped with shell 44 and inlet and outlet lines 45 and 46 for circulating heat exchange fluid. The reaction products are withdrawn through line 47, valve 48 to line 49 and passed thence to fractionator 50. Gaseous products may be removed through line 51 and valve 52. Gasoline which is substantially saturated and which may be used as an aviation base fuel is removed through line 53 and valve 54. Oil boiling above the desired end-point is withdrawn from fractionator 50 through line 55 and

valve 56, joining with line 31 and being returned in this manner to the high temperature catalytic cracking step. A portion of the oil may be withdrawn through line 107 and valve 108. The temperature at which reactor 1 is operated is within the range of approximately 500-900° F. Reactivation gases are introduced through line 57, line 58, valve 59, entering tube 60 which is disposed in reactor 3. This reactor is similar to 1 and 2, being equipped with shell 61 and inlet and outlet lines 62 and 63 for the circulation of heat exchange fluid. The reactivation gases leave the system through line 64, valve 65, line 66 and may be vented to the atmosphere, or a portion of the gas may be recirculated by means not shown. Another portion of reactivation gas passes through line 67, valve 68 to tube 69, which is disposed in reactor 4, similar to reactors 1, 2, and 3, and equipped with shell 70 and inlet and outlet line 71 and 72 for the circulation of heat exchange medium. The temperature of this reactor is decreased during the reactivation step to the level of reactor 1. The temperature of reactivation in reactor 3 begins at approximately the temperature employed in reactor 2 and is carried out at a level not to exceed approximately 1500° F. and preferably of the order of 1300° F. The reactivation gases are removed through line 73, valve 74 and line 66. After a time governed by the state of activity of the catalyst in the various reactors, the flows are switched and the next phase of the cycle is begun. In this phase the products of the higher temperature catalytic cracking from line 39 are passed through line 75 and valve 76 into reactor tube 69 in reactor 4 at a temperature of 500-900° F. and thence through line 77 and valve 78 to line 49, fractionator 50, and then as previously described. The raw oil charging stock from line 13, together with the recycle stock, is passed through line 79 and valve 80 to reactor 1 which is being operated in the high temperature range of 800-1200° F. and is then passed through line 81 and valve 82 to line 23. At the same time, reactivation gases are passed from line 57 through line 83 and valve 84 to reactor 2 and thence through line 85 and valve 86 to line 66. Reactivation is carried out at a temperature of approximately 900-1500° F. during this stage of operation. Reactivation gases from line 57 are passed also through line 58 and valve 59 to reactor 3 and thence through line 64 and valve 65 to line 66. During this interval the temperature in reactor 3 is brought back to the approximate range of 500-900° F. After a suitable interval, the valve settings are changed to those for the third phase of the cycle, in which reactor 3 is processing in the lower temperature range, reactor 4 is processing in the higher temperature range, reactor 1 is being reactivated in the higher temperature range and reactor 2 is being returned to the lower temperature range. This is accomplished by passing the raw oil charge from line 13 through line 87 and valve 88 to reactor 4, which is processing at a temperature of 800-1200° F. The reaction products are passed through line 89 and valve 90 to line 23 and fractionator 24. At the same time the products of the high temperature catalytic cracking from line 39 are passed through line 91 and valve 92 to contact with the freshly reactivated catalyst in reactor 3 and thence by means of line 93 and valve 94 to line 49 and fractionator 50. Reactivation gases from line 57 enter reactor 1 through line 95 and valve 96

and are exhausted through line 97 and valve 98 to line 66. Reactivation is carried out at the higher temperature level during this period. At the same time reactivation gases from line 51 are passed through line 83 and valve 84 to reactor 2 and thence are exhausted through line 85, valve 86 and line 66. The temperature is returned to the lower range during this step. After a suitable interval the valve settings are switched to those of the fourth phase of the cycle in which charging stock from line 13 is passed through line 99 and valve 100 to reactor 3, which is operated in the higher temperature cracking range. The products pass through line 101 and valve 102 to line 23 and thence to fractionator 24. The hydrocarbons from line 39 are passed through line 103 and valve 104 to reactor 2 which contains freshly reactivated catalyst. The reaction products are removed through line 105, valve 106 and line 49 to fractionator 50. At the same time reactivation gases from line 57 are introduced into reactor 4 through line 67 and valve 68 and removed through line 13, valve 74 and line 66. Simultaneously reactivation gases pass through reactor 1 to line 95, and valve 96 and are exhausted through line 97, valve 98 and line 66, the temperature of reactor 1 being brought back to the lower temperature range during this step. After a suitable interval the valve settings are again changed to those for the first phase, thus beginning the next cycle. In the interest of simplicity, a case has been described involving only four reactors. It should be understood, however, that a larger number may be used, thereby permitting the time during which a reactor remains at any particular processing or reactivation condition to be independently fixed.

According to one alternative within the scope of the present invention, a part or all of the oil from line 31 which is made up of insufficiently converted oil from fractionators 24 and 50 may be passed through line 32 and valve 32' to line 33 and thence to the lower temperature processing step for conversion into substantially olefin-free gasoline.

Certain pumps, heat exchangers, condensers, stabilizers and other auxiliary equipment necessary to the operation of such a process have been omitted in interests of simplifying the drawings.

Referring to Fig. 2, heat exchange media which may comprise any suitable liquid material such as mixtures of molten salts, metals or metal alloys and the like, is introduced through line 5, valve 6, line 7, pump 8, and passes through exchanger 9 wherein it may be heated or cooled as desired. When the medium is first introduced it is heated to the desired reaction temperature. The medium passes through line 10 to switching valve 11 and thence to reactor 1, entering through line 12 into shell 13. Reactor 1 contains catalyst tube 14, which as previously noted, may comprise reaction chambers or a plurality of manifolded tubes containing catalyst particles disposed therein. Reactor 1 in this case is being used to process hydrocarbon oil in the lower temperature range of 500-900° F. The medium passes through line 15 and switching valve 16, line 17, valve 18, line 19, switching valve 20, line 21 to shell 22 of reactor 4. This reactor is similar to reactor 1 and contains catalyst tube 23. In this step of the processing cycle, reactor 4 is being returned from the higher temperature reactivation to the lower temperature level,

namely, 500-900° F., reactivation gases being passed through the catalyst mass. The medium passes through line 24, switching valve 25 to line 7 where it is picked up by pump 8 and recirculated. When the system is filled with heat exchange medium, valve 6 is closed. Line 5 and valve 6 may be used as a means of draining the system when the plant is shut down.

Sufficient molten medium to fill the second heat exchange system is introduced through line 26 and valve 27, passing into line 28 and pump 29. The molten mixture passes through exchanger 30 which may be a heater or cooler as is necessary for the particular operation being carried out. The salt passes through switching valve 11, line 31, switching valve 16, line 32 to reactor 2, which is similar to reactors 1 and 4 and contains catalyst tube 33 disposed in shell 34. Reactor 2 is at this point being used to process hydrocarbon oil in the high temperature range, namely, 800-1200° F. The medium leaves reactor 2 through line 35, passes through switching valve 18, line 36 to reactor 3 which is similar to the other catalytic reactors and contains tube 37 disposed in shell 38. Reactor 3 is being reactivated in the higher temperature range, namely, 900-1500° F. The medium leaves the reactor through line 39, switching valve 20, line 40, switching valve 25, returning through line 41 to pump 29 whereby it is recirculated.

The switching valves are four-way valves which may be set in the positions indicated in Fig. 1 when operating as described. When changing the operation, it is necessary to change the valve settings in a manner indicated in Figs. 3, 4, 5, 6 and 7. In this manner, the temperature can be regulated for the successive processing and regenerating steps described and illustrated in Fig. 1. According to the valve setting just described, reactor 1 is processing at the lower temperature, reactor 2 processing at the higher temperature, reactor 3 reactivating at the higher temperature and reactor 4 reactivating at the lower temperature.

When the operation is shifted in the course of the regular cycle so that reactor 1 is processing at the higher temperature, reactor 2 regenerating at the higher temperature, reactor 3 regenerating at the lower temperature and reactor 4 processing at the lower temperature, the valves are in the following positions: valve 11 as in Fig. 3; 16 as in Fig. 4; 18 as in Fig. 5; 20 as in Fig. 6; and 25 as in Fig. 2.

In the next regular step in the operation, reactor 1 is reactivating at the higher temperature, reactor 2 reactivating at the lower temperature, reactor 3 processing at the lower temperature and reactor 4 processing at the higher temperature, the valve positions are valve 11 as in Fig. 3, valves 16, 18 and 20 as in Fig. 2, and valve 25 as in Fig. 7.

In the next step of the cycle wherein reactor 1 is reactivating at the lower temperature, reactor 2 processing at the lower temperature, reactor 3 processing at the higher temperature, and reactor 4 reactivating at the higher temperature, the valve positions are, valve 11 as in Fig. 2, and valves 16, 18, 20 and 25 as in Figs. 4, 5, 6, and 7, respectively.

The cycle is completed when the valves are switched to the original position whereby reactor 1 is processing at the lower temperature, reactor 2 processing at the higher temperature, reactor 3 reactivating at the higher temperature, and reactor 4 reactivating at the lower temperature, with the valves in positions illustrated in Fig. 2.

The following example is given to illustrate the usefulness and practicability of my invention when using a cracking catalyst under conditions to produce high yields of substantially saturated motor fuel. The example should not be construed as limiting the invention to the materials, apparatus or conditions indicated.

A catalyst comprising essentially precipitated silica having deposited thereon a minor proportion of precipitated alumina and precipitated zirconia was made into pellets and placed in a series of four catalytic reactors similar to those described in the foregoing specifications. A Mid-continent gas oil was cracked in the manner described in the specifications using the following conditions:

The lower temperature cracking step was carried out at 750° F. and a pressure of 100 pounds per square inch. The charge to this step comprised the catalytically cracked gasoline having added thereto approximately 25% of the recycle oil. The higher temperature cracking step was carried out at 950° F. and a pressure of approximately 50 pounds per square inch. The charge comprised a combined feed consisting of the raw oil plus the remaining portion of the insufficiently converted oil from both the high and low temperature cracking steps. A small portion of residual oil from the higher temperature cracking step was continuously withdrawn from the system. The high temperature reactivation was carried out at a maximum temperature of 1350° F. and the low temperature reactivation began at 1350° F. and the temperature was gradually decreased to 750° F. A mixture of flue gas containing approximately 3% of oxygen was used for conducting the regeneration. A portion of the reactivation gases was recycled.

A total yield of 69% of gasoline having an endpoint of 400° F. and a bromine number of 2 was obtained. The octane number was 78, which was increased to 95 upon the addition of 6 cc. of tetraethyl lead per gallon. In addition, 14% of polymer gasoline was produced, a large portion of which could be hydrogenated to produce iso-octane. Thus the total yield of gasoline amounted to 83%, of which a major portion was suitable for use as an aviation base fuel.

I claim as my invention:

1. A continuous catalytic process for converting normally liquid hydrocarbons into high yields of desirable products including substantially olefin-free high antiknock distillate suitable for use in aviation fuel which comprises converting said hydrocarbons in a plurality of substantially identical conversion zones serially arranged wherein the flow of hydrocarbons to, and the withdrawal of reaction products from the entire group of said conversion zones is substantially constant, and wherein the repeated sequence of steps is carried out in each of said conversion zones in a cyclic manner comprising a primary step wherein a stream of olefinic gasoline is contacted with a freshly reactivated catalyst under conditions of temperature and pressure adequate to produce a substantial yield of substantially saturated high octane distillate, a secondary step in which a separate stream of hydrocarbons heavier than gasoline is contacted with partially spent catalyst from the primary step at a relatively higher temperature to produce a substantial yield of relatively olefinic gasoline, a tertiary step in which the spent catalyst from the secondary step is partially reactivated by treatment with oxygen-containing gas at a temperature substantially

higher than that suitable for the primary step, a quaternary step in which reactivation is completed while the catalyst temperature is being restored to that suitable for said primary step, recovering the gasoline formed, and returning a portion of the insufficiently converted oil for further conversion.

2. A continuous process for converting hydrocarbon oil into high yields of substantially olefin-free gasoline which comprises converting said hydrocarbon oil in a plurality of conversion stages serially arranged wherein the repeated sequence of steps is carried out at each of said conversion stages, comprising a primary step of contacting an olefin-containing distillate produced as hereinabove described with a cracking catalyst under conditions of temperature and pressure adequate to effect substantial conversion thereof to substantially olefin-free gasoline, a secondary step of contacting hydrocarbon oil heavier than said distillate with said cracking catalyst under conditions of temperature and pressure adequate to effect substantial conversion thereof into olefin-containing distillate for conversion in said primary step, a tertiary step of partially reactivating said cracking catalyst used in said primary and secondary steps with an oxygen-containing gas at a temperature in excess of that used for processing in said primary step, and a quaternary step of completing reactivation of said cracking catalyst with an oxygen-containing gas while returning the temperature to that required for processing in said primary step, recovering the gasoline from said primary step, and returning a portion of the insufficiently converted oil for further conversion.

3. A continuous process for converting hydrocarbon oil into high yields of substantially olefin-free gasoline which comprises converting said hydrocarbon oil in a plurality of conversion stages serially arranged wherein the repeated sequence of steps is carried out at each of said conversion stages, comprising a primary step of contacting olefin-containing distillate produced as hereinabove described with a cracking catalyst under conditions of temperature and pressure adequate to effect substantial conversion thereof to substantially olefin-free gasoline, a secondary step of contacting hydrocarbon oil heavier than said distillate with said cracking catalyst under conditions of temperature and pressure adequate to effect substantial conversion thereof into olefin-containing distillate for conversion in said primary step, a tertiary step of partially reactivating said cracking catalyst which has been spent by use in said primary and secondary steps with an oxygen-containing gas at a temperature in excess of that used for processing in said primary step and a quaternary step of completing the reactivation of said cracking catalyst with an oxygen-containing gas while restoring the temperature to that required for processing in said primary step, maintaining those conversion stages operating in said primary and quaternary steps in heat exchange relationship by means of a circulating fluid heat exchange medium, maintaining those conversion stages operating in said secondary and tertiary steps in heat exchange relationship by means of a separate circulating fluid heat exchange medium, recovering the gasoline from said primary step, and returning a portion of the insufficiently converted oil for further conversion.

4. The process set forth in claim 1 wherein the cracking catalyst is selected from the group

consisting of silica-alumina, silica-zirconia and silica-alumina-zirconia.

5. The process set forth in claim 1 wherein the primary step is carried out at a temperature within the range of approximately 500-900° F. and a pressure of approximately 50-1000 pounds per square inch and the secondary step is carried out at a temperature within the range of approximately 900-1200° F. and a pressure of substantially atmospheric to 100 pounds per square inch.

6. A continuous process for converting hydrocarbon oil into high yields of substantially olefin-free gasoline which comprises converting said oil in a plurality of catalytic converters serially arranged wherein the repeated sequence of steps is carried out at each of said catalytic reactors, comprising a primary step of contacting an olefin-containing gasoline mixed with insufficiently converted oil produced as hereinafter described, with a cracking catalyst under conditions of temperature and pressure adequate to effect substantial conversion thereof into substantially olefin-free gasoline, a secondary step of contacting hydrocarbon oil heavier than gasoline with said cracking catalyst under conditions of temperature and pressure adequate to produce substantial conversion thereof into olefin-containing gasoline and insufficiently converted oil for conversion in said primary step, a tertiary step of partially reactivating said cracking catalyst used in said primary and secondary steps with an oxygen-containing gas at a temperature in excess of that used for processing in said primary step and a quaternary step of completing the reactivation of said cracking catalyst with an oxygen-containing gas, while returning the temperature to that required for processing in said primary step, maintaining said primary step and said quaternary step in heat exchange relationship by means of a circulating fluid heat exchange medium, maintaining said secondary step and said tertiary step in heat exchange relationship by means of a separate circulating fluid heat exchange medium, recovering the gasoline from said primary step and withdrawing a minor portion of residue unsuitable for further conversion.

7. A continuous process for converting hydrocarbon oil into high yields of substantially olefin-free gasoline which comprises converting said hydrocarbon oil in a plurality of catalytic reactors serially arranged wherein a repeated sequence of steps is carried out at each of said reactors, comprising a primary step of contacting olefin-containing reaction products of catalytic cracking produced as hereinafter described with a cracking catalyst under conditions of temperature and pressure adequate to effect substantial conversion thereof into substantially olefin-free gasoline, a secondary step of contacting hydrocarbon oil heavier than gasoline with said cracking catalyst under conditions of temperature and pressure adequate to effect substantial conversion thereof to olefin-containing reaction products for conversion in said primary step, a tertiary step of partially reactivating said cracking catalyst used in said primary and secondary steps with an oxygen-containing gas at a temperature in excess of that used for processing in said primary step and a quaternary step of completing

the reactivation of said cracking catalyst with an oxygen-containing gas while returning the temperature to that for processing in said primary step, recovering the gasoline from said primary step, returning a portion of the insufficiently converted oil to said secondary step, maintaining the reactors operating in said primary and said quaternary steps in heat exchange relationship by means of a primary heat exchange system, and maintaining the reactors operating in said secondary and tertiary steps in heat exchange relationship by means of a second heat exchange system.

8. In the catalytic conversion of hydrocarbon oils wherein a body of cracking catalyst is employed in an operating cycle including processing and regenerating steps, the method which comprises contacting olefinic gasoline with a body of cracking catalyst at a temperature of about 500-900° F. whereby to produce substantially saturated gasoline, then contacting hydrocarbon oil heavier than gasoline with said body at temperature in excess of 900° F., thereby forming olefinic gasoline, then partially reactivating said body of cracking catalyst by treatment thereof with oxygen-containing gas at a temperature in excess of 900° F., completing the reactivation of the catalyst body at a temperature in the approximate range of 500-900° F., and thereafter repeating the aforesaid cycle on said body of catalyst.

9. The process as defined in claim 8 further characterized in that olefinic gasoline produced from said oil heavier than gasoline is supplied to the first-mentioned conversion step.

10. The process as set forth in claim 1 wherein the cracking catalyst comprises essentially an acid-treated clay.

11. A continuous process for converting hydrocarbon oil into high yields of substantially olefin-free gasoline which comprises converting said hydrocarbon oil in a plurality of conversion stages serially arranged wherein the repeated sequence of steps is carried out at each of said conversion stages comprising a primary step of contacting olefin-containing gasoline produced as herein-after described with a cracking catalyst under conditions of temperature and pressure adequate to effect substantial conversion thereof into substantially olefin-free gasoline, a secondary step of contacting hydrocarbon oil heavier than gasoline with said cracking catalyst under conditions of temperature and pressure adequate to effect substantial conversion thereof into olefin-containing gasoline for conversion in said primary step, a tertiary step of partially reactivating said cracking catalyst used in said primary and secondary steps with an oxygen-containing gas at a temperature in excess of that used for processing in said primary step, and a quaternary step of completing the reactivation of said catalyst by treatment with an oxygen-containing gas while returning the temperature to that required for processing in said primary step, recovering the gasoline from said primary step, passing the part of the reaction products from said primary step boiling above the gasoline range to said secondary step, and recycling a portion of the insufficiently converted oil from said secondary step.
